Primary Examiner — Prabhakar Deshmukh(74) *Attorney, Agent, or Firm* — Patent Law Office of Rick Martin, P.C.(57) **CLAIM**

The ornamental design for an EXP guitar key, as shown and described.

DESCRIPTION

FIG. 1 is a perspective view of an EXP guitar key showing my new design;

FIG. 2 is a top plan view thereof;

FIG. 3 is a bottom plan view thereof;

FIG. 4 is a left side elevation view thereof;

FIG. 5 is a right side elevation thereof;

FIG. 6 is a front elevation thereof; and,

FIG. 7 is a rear elevation thereof.

The broken lines indicate unclaimed portions of the design and form no part of the claimed design.
